UNITED STATES PATENT OFFICE

HUGO JUNKERS, OF DESSAU, GERMANY

DIRECTIONAL CONTROLLING MEANS FOR AIRCRAFT

Application filed January 4, 1929, Serial No. 330,332, and in Germany January 14, 1928.

My invention refers to directional controlling means for aircraft and more especially flying machines and has for one of its objects to provide means whereby the operation of such controlling means is facilitated and rendered more efficient and reliable.

In the drawings affixed to this specification and forming part thereof a great number of different modifications of a directional controlling means applied to an aircraft embodying my invention is illustrated diagrammatically by way of example.

Directional controlling means as a rule consists of a fin or damping surface and a rudder arranged immediately at the rear of the fin. It has already been suggested to rock not only the rudder but also the fin in the same direction so that the angle through which the rudder moves with respect to the axis of the system, is larger than the angle through which the fin moves. It has also been suggested to arrange the fixed pivot of the fin outside the pivot of the rudder so that the pivot of the rudder moves bodily with the fin.

My invention relates to directional controlling means of the last-mentioned type and its principal object is to provide mechanism which, notwithstanding its great simplicity, effects by positive means the desired differential displacement of the fin and the rudder.

In reducing my invention to practice I prefer providing an arm on the rudder which projects from the side thereof, and I connect the end of this arm with one end of a rod, the other end of which is connected with the main control at a point far in advance of the pivot of the fin.

The pivot of the rudder may be arranged at the rear end of the fin or at any point between the rear end and the pivot of the fin without departing from my invention.

The part which is pivoted to the fin has been referred to as "the rudder" but it is to be understood that I am not limited to rudders, but that my invention may also be applied to elevators without departing therefrom.

In the drawings—
50 Fig. 1 is a partly sectional elevation of a

fin, a rudder and a mechanism for operating the fin and the rudder,

Fig. 2 is a plan view of an airplane to which the fin and rudder are fitted.

Referring now to the drawings, 1 is the fin which is pivoted on the fuselage of the airplane at 3, 2 is the rudder, 4 is its pivotal connection with the fin, 5 is an arm on the fin, 6 is a control rod which is linked to the arm 5 at 55. 62 is an arm on the rudder 2, and 65 is a rod which is pivotally connected with the arm 62 at its end 63 while its other end 66 is pivoted to a part on the rod 6, for instance a nut 56 which is adapted to be displaced on the threaded end 57 of the rod 6 by means of a hand wheel 58. The point 66 is far in advance of the pivot 3 of the fin, and also of its arm 5. When the rod 6 is moved the point 63 of the arm 62 on the rudder 2 describes a curve resulting from the longitudinal displacement of the point 66 and the rocking movement of the pivot 4.

A is the axis or neutral line of the system. In the initial position the pivots 3 and 4 and the trailing edge of the rudder 2 are all in the line A. When the fin 1 is rocked to the left as shown in Fig. 1 the rudder is also rocked about its pivot 4 but to a larger angle. The neutral position of the system can here be varied by displacing the link point 66 on the rod or wire.

Referring now to Fig. 2, 7 is the fuselage of an airplane, 8 and 9 are its wings, 10 is the cockpit and 11 is the propeller.

12 is a control rod which extends from the cockpit to the rear of the fuselage 7, 13 is a double-armed lever on the fuselage to one arm of which the rod 12 is hinged at 14, the rod 6 being hinged to its other arm at 15.

16 is a horizontal stabilizer at the end of 90 the fuselage and 17 is an elevator.

I wish it to be understood that I do not desire to be limited to the exact details of construction shown and described for obvious modifications will occur to a person skilled in the art.

In the claims affixed to this specification no selection of any particular modification of the invention is intended to the exclusion of other modifications thereof and the right 100

to subsequently make claim to any modification not covered by these claims is expressly reserved.

I claim:—

- 6 1. In an aircraft in combination, a damping fin mounted for rocking movement, a surface pivotally connected with said fin at a point outside the point about which said fin rocks, an arm extending from said fin, a control rod linked to said arm, an arm extending from said surface, and a rod extending from said arm on said surface to said control rod and connected to said rod at a point far in advance of the point about which said fin 10 rocks.
- 15 2. In an aircraft in combination, a damping fin mounted for rocking movement, a surface pivotally connected with said fin at a point outside the point about which said fin rocks, an arm extending from said fin, a control rod linked to said arm, an arm extending from said surface, a rod extending from said arm on said surface to said control rod and connected to said rod at a point far in advance of the point about which said fin 20 rocks, and means for varying the position of said connecting point on said control rod.
- 25

In testimony whereof I affix my signature.
